CLAIM

The ornamental design for a combination jacket and knapsack, as shown and described.

DESCRIPTION

FIG. 1 is a rear perspective view of a combination jacket and knapsack showing our new design;

FIG. 2 is a front elevational view thereof;

FIG. 3 is a right side elevational view of FIG. 2, the left side being a mirror image;

FIG. 4 is a rear elevational view of FIG. 2;

FIG. 5 is a top plan view of FIG. 2;

FIG. 6 is a bottom plan view of FIG. 2;

FIG. 7 is a rear perspective view of FIG. 1, the hood shown exposed; and,

FIG. 8 is a rear perspective view of FIG. 1, the knapsack being removed.

The broken lines shown throughout the views are understood to represent conventional stitching.
